CALCULATING INSTRUMENT

Benjamin L. Sites, Chicago, Ill., assignor to
Miehle Printing Press and Manufacturing Com-
pany, Chicago, Ill., a corporation of Illinois

Application July 5, 1940, Serial No. 343,978

18 Claims. (Cl. 235—61)

The current invention pertains to computing or calculating appliances whereby to determine data dependent upon at least three variables, as, for instance, in the case where a mathematical expression can be set up involving not less than three variables with a fourth or fourth and fifth unknown depending upon such three variables with continuous or discontinuous function, as, for example, assume that it becomes necessary to calculate the intensity of light falling at the tip of a man's shadow as he walks directly away from a source of elevated light, or assume that it is desired to know the height of an airplane by someone on the ground.

This new appliance is perhaps peculiarly and especially well adapted for ascertaining certain photographic data, as for instance, if one has a photographic-negative, and it is desired to make a positive photographic-transparency through it with definite physical characteristics, the calculating-instrument of this novel type can be used to distinct advantage, although it is to be understood that the principles underlying the construction and mode of operation of the instrument are in no sense confined to such specific employment.

To enable those acquainted with this craft and art to more fully understand the invention, both from structural and functional standpoints, thus affording a viewpoint of the various uses to which such instrument may be satisfactorily put, a present preferred embodiment of the invention has been illustrated in the accompanying drawings forming a part of this specification and to which reference should be had in connection with the following detailed description, and, for simplicity, like reference numerals have been used to designate the same parts throughout the views.

In these drawings:

Figure 1 is a top plan view of the novel instrument;

Figure 2 is a front face-view of the appliance;

Figure 3 is a longitudinal section on line 3—3 of Figure 1;

Figure 4 is a cross-section on line 4—4 of Figure 1; and

Figure 5 is a section on line 5—5 of Figure 1 on a somewhat enlarged scale.

Referring to these several views of the drawings, it will be noted that the casing or housing of the instrument, characterized 11 as a whole, has front, side and rear walls 12, 13, 13 and 14, respectively, and also has a top wall 15.

Rotatably mounted in suitable aligned bearings 16 and 17 in the front and back walls 12 and 15

14 is a shaft 18 extended through the front wall 12, as shown in Figure 3, and, to such forwardly-protruding end-portion of the shaft is keyed the hub 19 of a round disc or dial 21, the circular periphery of which is graduated in photographic-densities at 22 (Fig. 1), and, to facilitate turning or rotary adjustment of such dial, the hub 19 is supplied with an accessible, outstanding, radially-disposed handle 23.

Also fixedly mounted on such shaft inside of the housing, so as to turn with the shaft, is a cylindrical-drum 24 having on its surface a series of longitudinal rows of numerals 25, each numeral of which represents a photographic or emulsion developer-strength, and, by turning the shaft and drum, any one row of such indicia may be brought into register with a narrow, elongated slot or window 26 through the top-wall 15 of the encasing housing, thus rendering that particular row only visible to the operator of the apparatus.

In order to lock the dial 21 and its associated drum 24 in any one of their several positions of angular adjustment, the dial is externally provided with a circular series of radially-disposed holes 27, any one of which may receive a spring-pressed, manually-retractable lock-bolt 28.

The teeth of a small gear 31 (Figs. 3 and 4), fixed on and rotatable with shaft 18, mesh with those of a suitably-journalized companion-gear 32, the teeth of the latter meshing with those of a slidably-mounted rack 33 adapted to travel cross-wise of the apparatus.

By means of an upwardly-extended screw 34 mounted on an end portion of the rack-bar 33 and projecting up through a slot 35 through the top wall of the instrument, a relatively-long, lengthwise-slotted arm 36, just above the top wall 15, is fulcrumed at one end to the rack 33, and, from what precedes, it will be clear that, as shaft 18 is turned by its operating-handle 23 to bring any desired graduation of the density-scale 22 into register with the zero point of a companion or complementary density-graduated scale 37 on the upper face of a cross-bar 48 mounted on the top-wall 15 parallel to the line of travel of the fulcrum-screw 34, the fulcrumed end of the arm 36 will be correspondingly moved.

The reading on dial 21 with relation to the zero of scale 37, or with reference to an index-line 55 in register therewith, will always be the same as the location of the fulcrum of the arm 36 with relation to scale 37.

The path of travel of the axis of the fulcrum-screw 34, which is at a right-angle to the axis of the drum or cylinder 24, may be considered as

a base-line of a rectilinear-system of coordinates. The undercut, longitudinal slot in arm 38 (Fig. 5) is provided with a correspondingly-shaped slide 38 therein, which has an associated block 39 fitting and slideable in the lengthwise slot 40 of bar 41, such member 39 having an upper, integral section 43 above bar 41 and wide enough to partially overlap the bar laterally, and, in order that the two crossing, slotted members 36 and 41 may be maintained in the specified relation and may be temporarily locked in any desired position or relation of adjustment, the block 39, 43 has a hole therethrough accommodating a screw 44 on which the element 39, 43 may turn, the lower end of the screw being threaded to engage in a threaded hole in the element 38, the screw being provided with an accessible knurled knob 45 by means of which it may be tightened and loosened to lock the parts together or to free them for adjustment with relation to one another, the block 43 having an index-line in register with the intersecting axes of the parts 36 and 41 coaxing with the density-graduations of a scale 42 along one edge of the slot 40 of bar 41.

The end of bar 41 is fixedly mounted in any approved manner in and movable with a slide 46 (Fig. 5) occupying and manually adjustable along a groove between a bar 47 secured to the top of the appliance parallel to slot 35 and bar 48, hereinbefore referred to, and also parallel to slot 35. An index-line 49 on slide 46 in register with the axis of the lengthwise slot 40 of bar 41 operates with the density-scale 37 on the top face of bar 48 to indicate the position of adjustment of bar 41, which, as will be observed, as well as its slot 40, are exactly at a right-angle to the base-line mentioned above.

Slide 46 and bar 41 which it carries may be locked in any position of adjustment by a set-screw 50 extended through the slide 46 and arranged and designed when in locking relation to press or bear on the top face of bar 47, a portion of the slide underlying a part of bar 48 as presented in Figure 5.

The zero of scale 42 may or may not be in register with the specified base-line depending upon the nature of the calculation undergoing solution by the instrument.

Now does the density-scale 42 need to have its graduations spaced apart exactly like those of scale 37, and, in fact, in the drawings scale 42 is more condensed than scale 37 in order to decrease the size of the apparatus.

As is clearly portrayed, the long, undercut slot of arm 36 accommodates another slide 51 (Fig. 3) equipped with a handle or knob 52 so that such element 51 may move lengthwise in the slot, the center of member 51 being pivotally connected to a slide 53 reciprocatory in the housing slot 26, hereinabove referred to, such member 53 having therethrough a small window 54 through which one only of the numerals in the underlying row on the cylinder 24 is displayed at a time.

In this connection, it should be observed that the axis of slot 26 through the top wall of the casing is always in register with the zero-line 55 of scale 37 which also constitutes an index cooperating with the graduations 22 of the dial 21, the apertures 27 in the dial being so located that when any one is entered by the lock-bolt 28, one row only of numerals will be in register with the slot or elongated window 26.

As is illustrated in Figures 1, 2 and 3, dial 22 has angularly-adjustably mounted on its front face a ring 61 held in any desired position of ad-

justment by a plurality of screws 62, 62 occupying threaded holes in dial 22 and partially overlapping the face of the ring by extending beyond the circular boss 63 of the dial on which the ring is mounted.

On its circular periphery, directly adjacent to the density-scale 22, this ring, which has the same outside diameter as the dial 21, has a graduated exposure-scale 64, the correct adjustment of the latter with relation to the scale 22 being determined experimentally or from furnished data, each batch of light-sensitive emulsion bearing its own specific number.

Assuming that it is desired to make a photographic positive-transparency with definite physical characteristics from an available negative, the high-light density of such transparency is determined from the instrument when the latter is set or adjusted from the known or determinable high-light density of the negative which we will assume in this case as 1.8, and, by unlocking the dial 21 and turning it the graduation 1.8 is brought into register with the stationary index-line 55, whereupon the dial is again locked in this relation.

Such operation has turned the graduated-drum to bring the proper or corresponding row of figures 25 into register with the display-opening 26 and has also, through the gear-and-rack mechanism shifted the fulcrum 34 of the arm 36 into a position in register with the like density graduation or value on scale 37, so that the position of such fulcrum from the zero-line 55 and the correct row of displayed numerals on the cylinder are in harmony or consonance.

Then slide 46 and its slotted bar 41 are slid along until the index-line 49 on slide 46 registers with the graduation on scale 37 corresponding to the shadow-density of the negative, this being 40 1.00 in the instant case, as shown in Figure 1.

One of the ascertained or established characteristics of the positive-transparency is one item of its known density-gradient, sometimes called its density-range, and the member 38—39—43 is adjusted along the slot 40 of bar 41 until its 45 index-line registers with the item valuation on scale 42, such operation determining the slope, inclination or obliquity of the arm 36 whose angular position is necessarily determined by the position of the compound-block 38—39—43 in the slot of bar 41, such block being then temporarily locked in the required position by tightening screw 44 by its knob 45.

As will be readily understood, the rocking or angular adjustment thus effected has through 55 its conjoint members or slides 51, 53 brought the window 54 into a definite position displaying therethrough a numeral indicative of the strength of the developer to be used for a pre-determined period of time in developing the light-sensitive emulsion exposed through the 60 negative for a period of the time shown on the scale 64 of the adjusted ring 61 opposite the index-line 55, which, of course, in this particular case, is opposite the graduation 1.8 of the dial 21.

Therefore, by this calculating-instrument, we have determined the initial unknown factors, exposure-time and developer-strength, necessary to produce the required positive-transparency from the negative, the development period at a suitable temperature having been preliminarily fixed.

Thus, with the three variables (a) the position of the fulcrum 34, (b) the position of the slide 46 and bar 41, and (c) the position of the 70 slide in the slot of the bar 41, we have been

able to determine or establish two other factors, developer-strength and exposure, involved in the solution of the problem presented.

Those acquainted with this craft and art will readily understand that the invention, as defined by the appended claims, is not necessarily limited and restricted to the precise and exact details of structure herein set forth and that modifications may be resorted to without departure from the heart and substance of the invention and without the loss of any of its substantial benefits.

I claim:

1. In a calculating-instrument having supporting-means for the component parts of the instrument hereinafter set forth, a plurality of series of indicia, a rock-arm cooperating with said indicia, a fulcrum for said rock-arm adjustable in a definite path in the plane of movement of said rock-arm around said fulcrum, and means including graduations to indicate individually the various positions of adjustment of said fulcrum, the novel combination of, means to denote the particular one of said indicia-series which corresponds to each adjusted position of said fulcrum, an element disposed at an angle to the direction of adjustment of said fulcrum and adjustable in said direction and independently of the adjustment of said fulcrum, means to indicate each adjusted position of said element including graduations, and means, including additional graduations, dependent upon the relation of said rock-arm to said element to define the single one of said additional graduations corresponding to each adjusted position of said rock-arm, said rock-arm identifying that single index of the denoted one of said indicia series corresponding to each of its adjusted positions.

2. In a calculating-instrument having supporting-means for the component parts of the instrument hereinafter set forth, a plurality of series of indicia, a rock-arm cooperating with said indicia, a fulcrum for said rock-arm adjustable in a definite path in the plane of movement of said rock-arm around said fulcrum, and means including graduations to indicate individually the various positions of adjustment of said fulcrum, the novel combination of, means to denote the particular one of said indicia-series which corresponds to each adjusted position of said fulcrum, an element disposed at an angle to the direction of adjustment of said fulcrum and adjustable in said direction and independently of the adjustment of said fulcrum, means connecting said rock-arm and element and adjustable along both, means, including graduations, to indicate each adjusted position of said element, means, including additional graduations, to show each adjusted position of said connecting-means along said element, and means additional to, and actuated by, said rock-arm to identify that single index of the denoted one of said indicia series corresponding to each adjusted position of said rock-arm.

3. The novel combination of means set forth in claim 1, in which the direction of adjustment of said element is straight and in which said angle is at a right-angle.

4. The novel combination of means set forth in claim 2, in which the direction of adjustment of said element is straight and in which said angle is a right-angle.

5. The novel combination of means set forth in claim 1, in cooperation with means coupling said fulcrum and said denoting-means together

whereby the adjustment of the position of said fulcrum simultaneously causes the denotation of the corresponding one of said indicia-series.

6. The novel combination of means set forth in claim 2, in cooperative relation with means coupling said fulcrum and said denoting-means together whereby the adjustment of the position of said fulcrum simultaneously causes the denotation of the corresponding one of said indicia-series.

7. The novel combination of means set forth in claim 1, in cooperation with means coupling said fulcrum and said denoting-means together whereby the adjustment of the position of said fulcrum simultaneously causes the denotation of the corresponding one of said indicia-series, and in which the direction of adjustment of said element is straight, and in which said angle is a right-angle.

8. The novel combination of means set forth in claim 2, in cooperation with means coupling said fulcrum and said denoting-means together whereby the adjustment of the position of said fulcrum simultaneously causes the denotation of the corresponding one of said indicia-series, and in which the direction of adjustment of said element is straight, and in which said angle is a right-angle.

9. The novel combination of means set forth in claim 1, in cooperative relation with supplemental graduated-means alongside of, and adjustable relatively to, the graduations of said means representing the various positions of adjustment of said fulcrum.

10. The novel combination of means set forth in claim 2, in cooperative relation with supplemental graduated-means alongside of, and adjustable relatively to, the graduations of said means representing the various positions of adjustment of said fulcrum.

11. The novel combination of means set forth in claim 1, in which said indicia represent photographic developer-strengths, in which said graduations represent photographic-densities, and in cooperative relation with supplemental photographic-exposure graduated-means alongside of, and adjustable relatively to, the graduations of said means representing the various positions of adjustment of said fulcrum.

12. The novel combination of means set forth in claim 2, in which said indicia represent photographic developer-strengths, in which said graduations represent photographic-densities, and in cooperative relation with supplemental photographic-exposure graduated-means alongside of, and adjustable relatively to, the graduations of said means representing the various positions of adjustment of said fulcrum.

13. The novel combination of means set forth in claim 1, in which said indicia represent photographic developer-strengths, in which said graduations represent photographic-densities, in which said direction of adjustment of said element is straight, in which said angle is a right-angle, in cooperative relation with supplemental photographic-exposure graduated-means alongside of, and adjustable relatively to, the graduations of said means representing the various positions of adjustment of said fulcrum, and in cooperative relation with means coupling said fulcrum and said denoting-means together whereby the adjustment of the position of said fulcrum simultaneously causes the denotation of the corresponding one of said indicia-series.

14. The novel combination of means set forth

in claim 2, in which said indicia represent photographic developer-strengths, in which said graduations represent photographic-densities, in which said direction of adjustment of said element is straight, in which said angle is a right-angle, in cooperative relation with supplemental photographic-exposure graduated-means alongside of, and adjustable relatively to, the graduations of said means representing the various positions of adjustment of said fulcrum, and in cooperative relation with means coupling said fulcrum and said denoting-means together whereby the adjustment of the position of said fulcrum simultaneously causes the denotation of the corresponding one of said indicia-series.

15. The novel combination of means set forth in claim 1, in cooperative relation with a drum displaying on its external surface said plurality of series of indicia disposed longitudinally of said drum, and means to turn said drum on its axis simultaneously with the adjustments of said fulcrum to bring into operative position that one of said series corresponding to each position of adjustment of said fulcrum, and in which the direction of adjustment of said element is at right-angles to the axis of said drum.

16. The novel combination of means set forth in claim 2, in cooperative relation with a drum displaying on its external surface said plurality of series of indicia disposed longitudinally of said drum, and means to turn said drum on its axis simultaneously with the adjustments of said fulcrum to bring into operative position that one of said series corresponding to each position of adjustment of said fulcrum, and in which the direction of adjustment of said element is at right-angles to the axis of said drum.

17. The novel combination of means set forth in claim 1, in which said supporting-means includes a housing, and in cooperative relation with a suitably-journalized shaft at least in part in said housing, means to turn said shaft manually, a

drum in said housing rotatable with said shaft and displaying on its exterior surface said plurality of series of indicia in longitudinal rows, means actuated by said shaft to adjust said fulcrum correspondingly and simultaneously, means to releasably lock said shaft, drum and fulcrum in their several positions of adjustment, and in which said denoting-means includes a window in said housing through which to display one only of said series of indicia at a time, in which the adjustment of said element is in a path at right-angles to the axis of said drum, and in which said fulcrum position indicating-means includes a graduated-dial rotatable with said shaft.

18. The novel combination of means set forth in claim 2, in which said supporting-means includes a housing, and in co-operative relation with a suitably-journalized shaft at least in part in said housing, means to turn said shaft manually, a drum in said housing rotatable with said shaft and displaying on its exterior surface said plurality of series of indicia in longitudinal rows, means actuated by said shaft to adjust said fulcrum correspondingly and simultaneously, means to releasably lock said shaft, drum and fulcrum in their several positions of adjustment, and in which said denoting-means includes a window in said housing through which to display one only of said series of indicia at a time, in which the adjustment of said element is in a path at right-angles to the axis of said drum, in which said fulcrum position indicating-means includes a graduated-dial rotatable with said shaft, and in which said identifying-means includes a multiple-slide having two sections hinged together with one section slidable along said rock-arm and the other section slidable in said housing-window and equipped with a window through which the proper single index corresponding to the position of said rock-arm is displayed.

BENJAMIN L. SITES.
